his Attorney

UNITED STATES PATENT OFFICE.

CHARLES A. ROBERTS, OF CANON CITY, COLORADO.

HOSE-HOLDER.

1,233,916.

Specification of Letters Patent. Patented July 17, 1917.

Application filed March 10, 1916. Serial No. 83,339.

To all whom it may concern:

Be it known that I, CHARLES A. ROBERTS, a citizen of the United States, residing at Canon City, in the county of Fremont and 5 State of Colorado, have invented certain new and useful Improvements in Hose-Holders, of which the following is a specification.

My invention relates to hose holders such 10 as are used to support the nozzle attached to the end of a lawn or garden hose to hold it off the ground and pointed in a particular direction.

The principal object of my invention is 15 to provide a simple and inexpensive hose holder which is strong and easy to manipulate.

It is also my object to provide a hose holder so constructed as to tightly grasp 20 the hose or nozzle and also designed so that the water pressure will not turn the holder from the position in which it is set in the ground.

The above and other objects and the novel 25 features of my invention will be apparent from the following description taken in connection with the drawing, in which:—

Figure 1 is a perspective view of a hose holder embodying my invention, showing 30 the same in use;

Fig. 2 is a plan view of a blank from which the holder is made;

Fig. 3 is a front view of the holder, and 35 Fig. 4 is an edge view of the same.

Referring to the drawing, the hose holder is made of a single length or bar 10 of metal, preferably of sheet metal of sufficient thickness so that it will form a rigid support which will not bend when forced into 40 the ground or due to the weight of the hose and nozzle carried by it. The bar 10 is substantially rectangular in transverse section so that it will not turn when set in the ground.

5 The lower end of the bar 10 is pointed as at 11 and the inclined edges 12 of the pointed end are beveled or sharpened, as shown, so that the holder will more readily enter the ground.

The handle and the nozzle and hose grasping means at the upper end of the holder are formed by first cutting a slit 13 into the bar from the upper end thereof, as indicated in Fig. 2. The parts 14 and 15 on opposite sides of the slit are then twisted

at 16 so that the faces thereof formerly in a plane with the broad side of the bar, will be turned at right angles to the broad side of the bar. The arms 14 and 15 are then spread apart and bent so as to provide a 60 substantially circular space 17 between them to receive the nozzle N or hose H. The bottom of the space 17 tapers down to a point as at 18 and the hose or nozzle when in place will be held by the wedging action 65 of the edges 19.

The arms 14, 15 are bent inwardly at the points 20, 20, above the outward bends 21, 21. The distance between the bends 20, 20 is less than the diameter of ordinary hose 70 and nozzles, forming an entrance passage for the space 17 so that when the hose or nozzle is inserted into the space 17, the arms will exert a grasping or clamping action thereon to hold it tightly. Furthermore, 75 the arms 14 and 15 have sufficient flexibility or resiliency so they may be sprung apart to take a large nozzle or they will securely hold a small nozzle, which provides a holder adapted for a considerable range of sizes 80 of hose or nozzles. The flat faces of the arms 14, 15 bear against the nozzle or hose and this extended bearing surface keeps the hose or nozzle from turning in the holder due to water pressure, while the flat body 85 of the holder in the ground prevents the holder itself from turning.

Above the bends 20, 20 the arms 14 and 15 are bent on a curve upwardly, outwardly and downwardly as at 22, 22 providing finger grips or a handle whereby the holder may be readily set in the ground or withdrawn therefrom. These grips may also be used to press or spring the arms apart to remove or insert the hose or nozzle. 95

From the foregoing description it will be apparent that I have provided a simple and inexpensive unitary or integral holder, and one which may be easily manipulated. The arms at the top are made sufficiently flexible 100 to hold different sizes of hose, as is necessary to place the holder back of some nozzles. The holder post is flat and thin so that the holder can easily be placed in the ground and yet the water pressure can not swing or 105 change the position of the nozzle as it does in holders where the post is round.

While I have shown and described the holder in detail I do not wish to be limited to the exact construction disclosed as it will 110

be clear that minor changes may be made therein without departing from the spirit of the invention.

What I claim and desire to secure by Letters Patent is:

1. A metal hose holder consisting of a single post pointed at its lower end and having a forked part at its upper end, the part of the post adapted to enter the ground being of a cross-sectional shape which will resist the tendency of the water pressure to turn the hose holder about its longitudinal axis when it is in the ground, the forked upper part of the holder comprising two resilient arms adapted to receive and clamp a hose in the space between them, said arms having parts thereof extending toward each other to form an entrance passage to said space which is narrower than the space, said arms having bent portions to provide finger grips or a handle for the holder.
2. A one-piece hose holder made from a single piece of sheet metal and comprising a single post having a pointed substantially flat lower end adapted to be forced into the

ground, the flat formation of said post being adapted to resist the tendency of the water pressure to turn the holder about its axis, said post also having a forked upper end providing resilient arms adapted to receive and resiliently clamp a hose or nozzle in the space between them, the upper ends of said arms being bent to form finger grips at the upper end of the holder.

3. A one-piece hose holder consisting of a post having a pointed substantially flat lower end and a forked upper end, the forked end comprising two integral parts of said bar twisted to form two arms with bearing faces disposed at right angles to the plane of the lower end of the bar, said arms being resilient and curved so as to yieldingly engage and clamp a hose or nozzle between them.

In testimony whereof I affix my signature in the presence of two witnesses.

CHARLES A. ROBERTS.
